UNITED STATES PATENT OFFICE

PERRY T. DENMEAD, OF AKRON, OHIO, ASSIGNOR TO ADA DENMEAD AND JOHN W. DENMEAD, BOTH OF AKRON, OHIO, AND WILLIAM BYRIDER, OF CLEVELAND, OHIO

MATCH FOLDER

Application filed November 3, 1928. Serial No. 316,986.

This invention relates to matches and has particular relation to new and novel improvements in match packages in folder or book form.

5 Objects of the invention are to provide an attractive match package, containing matches of ordinary construction to be securely held therein whereby the same may be conveniently detached and used when desired.

10 A particular object is to provide a match package of the folder type which will be very efficient in use and which may be manufactured at a very low cost.

An additional object is to provide a simple, 15 inexpensive folder carrying a plurality of separate matches with each match adhesively secured therein whereby the folder when closed, will protect the matches and will be held in a closed position.

20 The above objects are accomplished and additional ends are attained by the novel construction, combination and arrangement of parts hereinafter described and illustrated in the accompanying drawing, wherein I have 25 shown a preferred form of the invention, it being understood that the invention is capable of various adaptations and that changes and modifications may be made or resort had to substitutions which come within the scope 30 of the claim hereunto appended.

In the drawings, like numerals of reference are employed to designate like parts as the same may appear in any of the several views and in which:—

35 Figure 1 is a perspective view of a match package constructed in accordance with this invention,

Figure 2 is a side view of same,

40 Figure 3 is a plan view showing a folder in a flat position,

Figure 4 is an edge view of same.

Proceeding now to a detailed description 45 of the invention, with reference to the particular adaptation thereof disclosed in the drawing, wherein I have shown a flat, rectangular blank which is provided with the scores 5 and 6 to form a folder having a base portion 7, a back portion 8 and a lid portion 9. The numeral 10 is used to denote matches 50 which are preferably of the ordinary stick

type, each being provided with an ignition head 11. The matches are arranged in parallel relation and are secured to the inner surface of the base portion 7 by means of the layer of adhesive 12 or other suitable means. 55

It will be seen that the main portion of each match 10 projects beyond the free end of the base portion 7. The adhesive 12 terminates in spaced relation to the free edge of the base portion 7 thereby forming a flap 7^a whereby the free end of the lid 9 may be received between the flap 7^a and the matches. The blank is folded approximately along the line 5 to extend along the rear sides of the matches 10^a, and is likewise folded approximately 60 on the line 6 whereby the lid 7 may be moved downwardly over the matches and inserted under the flap 7^a to securely hold the package 65 in a closed position.

The outer face of the base portion 7 is provided with an abrasive panel 13 which is coated with the abrasive or other substance with which the heads 11 of the matches 10 may be brought into forced contact for the purpose of igniting same. The outer face of the body 70 8 and the outer face of the lid 9 may be used to print suitable advertising matter thereon. 75

In use, the package is folded as shown in Figure 2 so that in its closed position it may be conveniently carried in the pocket. When 80 it is desired to use any of the matches, the lid 9 is folded back and the base 7 is turned forwardly whereby one of the matches may be quickly and conveniently detached therefrom. The match thus detached is then struck on the 85 panel 13 to ignite the same.

It will thus be seen that I have provided a match package which will be very convenient in use and which can be manufactured at an exceedingly low cost. 90

Having thus illustrated my invention and described the same in detail, what I claim as new and desire to secure by Letters Patent is:—

95 In a match package, a flat strip bent to form a folder having a base portion, a back portion and a cover portion and a plurality of independent stick matches arranged in parallel relation in a laterally extending row, the handle ends of said matches adhesively 100

secured to said base portion only, along an area extending in close spaced relation to the free end thereof, the back and cover portions of said strip being free whereby the 5 same may be opened to extend in the plane of the base portion and may be folded around said matches with one end of the cover portion inserted beneath the free end of the base portion to hold the package in a closed position.

10 In testimony whereof I have hereunto set my hand.

PERRY T. DENMEAD.
